H. S. FAHEY

THERMOSTATIC VALVE

Filed June 11, 1926

Inventor

H.S. Fahey

By Clarence O'Brien.

Attorney

UNITED STATES PATENT OFFICE.

HILARION S. FAHEY, OF GRAFTON, MASSACHUSETTS.

THERMOSTATIC VALVE.

Application filed June 11, 1926. Serial No. 115,267.

This invention relates to an improved thermostatic valve of the type adapted to be used in a steam heating system, and it has more particular reference to a valve of 5 this kind which is intended to be installed in the steam circulating pipe and be connected with the steam supply pipe and pipe section leading through one of the radiators.

Briefly, the invention comprises an appropriate casing with which the steam supply pipe and radiator conducting pipe may be connected, the casing being designed to house a novel thermostat and a valve operating means associated therewith, and 15 there being a by-pass for directing a portion of the steam directly upon the thermostat to insure efficient operation of the latter.

My principal object is to generally improve upon valves of this class by providing 20 one of comparative simplicity and durability including novel details arranged in a novel manner to insure the production of a practical device capable of accomplishing the desired result in a most efficient manner.

25 Other objects and advantages of the invention will become apparent from the following description and drawing.

In the accompanying drawing forming a 30 part of this application and in which like numerals are employed to designate like parts throughout the same:

The single figure represents a view in section and elevation of the complete valve showing the pipes connected therewith.

35 Referring to the drawings in detail, the reference character 1 designates the casing which is here shown as being open at its top and provided at its bottom and on diametrically opposite sides with suitable nipples 2, 40 3, and 4, respectively. The steam supply pipe 5 from the boiler (not shown) is connected with the nipple 2 and it will be noticed that the inner end of this nipple is fashioned so as to provide a beveled valve

45 seat 6. The pipe 7 which is connected with the nipple 4 leads to one of the radiators in the system (not shown). Connected with the remaining nipple 3 is a by-pass 8 made up of pipe sections and couplings as shown.

50 The upper end of this by-pass is attached to another nipple or coupling 9 forming a part of a removable closing plate 10 for the open top of the casing.

On the interior of the casing adjacent the 55 top is a bracket 11 with which an arch 12 is connected. The depending portion adja-

cent the bracket is formed with a guide slot 13 at its lower end and the other depending arm on the opposite end constitutes a support for an operating lever 14. It will be 60 noted that the lever is pivoted between its center at one end on the last named depending arm as indicated at 15. Moreover, the short end of the lever is provided with a counterbalancing weight 16. Attached 65 to the opposite end of the lever is a flexible element 17 which passes over pulleys 18 and 19 respectively and is connected with a valve 20 cooperable with the aforesaid seat 6.

It will be noted that the pulley 18 is supported on the standard 21 in the casing, while the pulley 19 is supported on the outer end of an upwardly inclined arm 22 extending from this standard. Attention is also directed to the fact that there is a connection 23 between the depending portion 24 of the arch and the adjacent wall of the casing. The thermostat 25, which is more or less conventional in design, is supported from the parts 12 and 23 in any suitable fashion. 70 The movable diaphragm of the thermostat is provided with a depending pin 26 which engages the intermediate portion of the aforesaid lever for rocking it and permitting the valve to close at a predetermined time. 75

80 From the foregoing it is obvious that the steam passing through the pipe 5 enters the casing when the valve is open and a portion of the steam passes through the by-pass 8 while the greater portion passes through the 90 pipe 7 through the radiator in the usual way. The thermostat is made to operate at a predetermined temperature and it is therefore obvious that the steam in acting on this, causes the downward movement of the pin 95 26. In so doing, the pin presses downwardly on the lever 14, thus overcoming the action of the weight 16 and allowing the valve 20 to drop by gravity and to engage the valve seat and to close the supply pipe 5. It will 100 thus be seen that instead of opening the steam valve on the radiator and allowing surplus steam to waste into the atmosphere, when the system becomes too hot, it will be automatically closed and a further supply of 105 steam to the radiator will be temporarily cut off.

110 From the foregoing description and drawings it will be seen that I have evolved and produced a novel contrivance for automatically cutting off the steam supply to a radiator when the system reaches a predetermined

temperature. Obviously, however, when the system cools down again and the thermostat resumes its normal state, the counterbalance weight 16 overbalances the valve 20 and raises it and permits the system to operate again. Naturally, this effects a considerable saving of fuel and yet keeps the temperature in the room at a nearly uniform state. These and other advantages and features of the invention have been made apparent and as the operation and construction of the invention is clear, a more lengthy description is thought unnecessary.

While the preferred embodiment of the invention has been specifically described and shown, it is to be understood that minor changes in shape, size, and arrangement of parts, may be resorted to within the field of invention claimed.

Having thus described the invention what I claim as new and desire to secure by Letters Patent is:—

1. In a thermostatic valve of the class described, a casing provided with a valve seat, a gravity lowered valve cooperable with said seat, a standard supported in the casing adjacent said valve, an arm carried by said standard, pulleys mounted on the upper end of the standard and the outer end of said arm, a pivotally mounted counter-balanced

lever supported above the valve and standard, a flexible operating connection between one end of the lever and said valve and a thermostat supported above said lever for operating it at a predetermined time.

2. In a thermostatic valve of the class described, a casing provided with a valve seat with which a supply pipe is adapted to be connected, a gravity lowered valve cooperable with said supply pipe for closing it at a predetermined time, a standard supported in the casing adjacent the valve, an arm carried by said standard, pulleys mounted on the standard and arm, a bracket supported in said casing, an arched member supported from said bracket, a counter balanced lever pivoted between its center and one end on one of the depending arms of the arch, the opposite end of the lever being movable in a guide slot in the remaining depending arms of said arch, a flexible operating connection between the valve and last named end of the lever, said connection being trained over said pulley, and a thermostat associated with said arch and including a vertically movable operating pin cooperable with the central portion of said lever.

In testimony whereof I affix my signature.

HILARION S. FAHEY.
